US00D820842S

(12) **United States Design Patent** (10) **Patent No.:** **US D820,842 S**
(45) **Date of Patent:** **** Jun. 19, 2018**

(54) **TOUCH SENSOR ARRAY**

(71) Applicant: **Sensel, Inc.**, Mountain View, CA (US)

(72) Inventors: **Ilya Daniel Rosenberg**, Mountain View, CA (US); **John Aaron Zarraga**, San Francisco, CA (US); **Brogan Carl Miller**, Davis, CA (US)

(73) Assignee: **Sensel, Inc.**, Mountain View, CA (US)

(**) Term: **15 Years**

(21) Appl. No.: **29/575,547**

(22) Filed: **Aug. 25, 2016**

Related U.S. Application Data

(63) Continuation-in-part of application No. 14/499,090, filed on Sep. 27, 2014, now Pat. No. 9,459,746, which is a continuation-in-part of application No. 14/314,662, filed on Jun. 25, 2014, now Pat. No. 9,001,082.

(57) **CLAIM**

The ornamental design for a touch sensor array, as shown.

DESCRIPTION

FIG. 1 is a front view of a touch sensor array showing my new design;

FIG. 2 is a rear view thereof;

FIG. 3 is a right view thereof;

FIG. 4 is a left view thereof;

FIG. 5 is a top view thereof;

FIG. 6 is a bottom view thereof;

FIG. 7 is a top front perspective view thereof;

FIG. 8 is a top rear perspective view thereof;

FIG. 9 is a top right front perspective view thereof;

FIG. 10 is a top right rear perspective view thereof;

FIG. 11 is a top left rear perspective view thereof;

FIG. 12 is a top left front perspective view thereof;

FIG. 13 is a bottom right front perspective view thereof;

FIG. 14 is a bottom right rear perspective view thereof;

FIG. 15 is a bottom left rear perspective view thereof; and,

FIG. 16 is a bottom left front perspective view thereof.

1 Claim, 16 Drawing Sheets
